CLAIM

The ornamental design for an oval rocking chair, as shown and described.

DESCRIPTION

FIG. 1 is a front view of an oval rocking chair, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof;

FIG. 9 is an exploded front perspective view thereof;

FIG. 10 is an exploded right side view thereof;

FIG. 11 is a top view of a chairback component thereof;

FIG. 12 is a bottom view of a chairback component thereof;

FIG. 13 is top view of a seat component thereof;

FIG. 14 is bottom view of a seat component thereof;

FIG. 15 is a top view of a right side component thereof; and,

FIG. 16 is a top view of a left side component thereof.
